AUTOMATIC PRINTING TELEGRAPH
EXCHANGE SYSTEM

George A. Locke, Glenwood, N. Y., assignor to
Bell Telephone Laboratories, Incorporated,
New York, N. Y., a corporation of New York

Application December 9, 1932, Serial No. 646,368

9 Claims. (Cl. 178—2)

This invention relates to telegraph switching systems and particularly to automatic switching printing telegraph or teletype systems.

An object of the invention is to utilize normally deenergized circuits extending between the sending and the receiving stations for selecting idle receiving printers and for transmitting, after selection, signals from the sending station to the selected receiving printer.

10. Another object is to overcome delays in communication caused by all the receiving printers being busy.

Still another object is to broadcast from one of the receiving printers to two or more of the 15 sending stations.

Heretofore, printing telegraph systems wherein in a group of receiving printers were so arranged that in response to the operation of a key at a sending station, the first idle receiving printer 20 of the group may be selected for receiving the transmitted message, the communication circuit extending from the sending station to the receiving station being normally closed. Should all the receiving printers of a group be found 25 busy by the sending station, the operator at the sending station will receive a signal indicating that she should restore the key and try again.

According to the present invention, a plurality of normally deenergized communication lines 30 respectively connect a plurality of sending stations to a central office whereat incoming calls are automatically distributed to a group of idle printers, the first idle printer of the group being selected by each incoming call. Should all the printers be 35 busy at the time a call is received at the central office, a busy lamp at an operator's position in the central office lights and the operator in response to this light connects an auxiliary teletypewriter to the calling line whereby the message may be 40 received at the central office. The auxiliary printer at the central office is further arranged to transmit messages to the printer at any one of the sending stations and to the printers at two or more sending stations simultaneously for 45 broadcasting purposes.

Among the features disclosed herein are the following:

1. The provision of a key at a sending or outlying station, the single operation of which selects 50 an idle printer at the central office, the selection of the printer being effective to start the printer motor at the sending station.

2. The provision at the central office of a lamp for each outlying station and an auxiliary printer 55 common to all outlying stations. The lamp serves

to indicate to the operator that all the main printers at the central office are busy and the auxiliary printer being adapted to be connected by the operator to the calling line associated with the lighted lamp, to pick up the message.

3. The system is so arranged that the central office may originate a call to a line on a broadcast to a group or all the lines simultaneously.

Other objects and features will appear in the following detailed description taken in conjunction with the following drawings.

Referring to the drawings:

Fig. 1 shows a schematic layout of a sending, or outlying station. It also shows a second sending station represented diagrammatically by a 15 block:

Fig. 2 schematically shows a portion of the equipment at the central office. The equipment shown in the upper and middle parts of the drawings represents that associated with the calling station shown somewhat in detail in Fig. 1. The equipment shown in the lower part, that is, within the block, is used when transmitting from the central office to the second outlying station shown in Fig. 1; and

Fig. 3 illustrates schematically the arrangement of the main printers, the auxiliary printer and the equipment used by the operator at the central office for picking up a message from an outlying station when all the main printers are 30 busy and for transmitting to the outlying stations either individually or for broadcast purposes.

Apparatus at an outlying station

Referring to Fig. 1 which shows the subscriber's 35 loop circuit at an outlying station A, the equipment shown therein comprises a printing telegraph sending and receiving unit 101. Unit 101 comprises a printer magnet 102, a set of sending contacts 103, a suitable motor 104, equipped with 40 a pair of motor control contacts 105 which will open by mechanical means when a motor stop signal is sent, and a break key 106. The motor in the circuit herein described is driven by alternating current. External of the printer telegraph 45 set or unit are the non-locking call key 107, an alternating current power supply 108, a rectifier 109, power connecting relays 110 and 111, a pulsing relay 112 and a loop connecting relay 113. Relays 110 and 112 are of the polar type. Another 50 outlying station B is also shown but in diagrammatic form.

Apparatus at the central office

Figs. 2 and 3 constitute equipment at the 55

central office. In Fig. 2 the tip conductor 115 and the ring conductor 116 of the outlying station group circuit are connected to the relay equipment at the central office for effecting the operation of 5 a rotary selector switch S which comprises three banks I, II and III of contacts. Polar relays 201 and 202 and non-locking key 203 constitute equipment whereby the operator at the central office may complete the necessary circuit for 10 transmitting messages to the outlying station A. Equipment hereinbefore mentioned in Fig. 2 is individual to the loop circuit of station A. There is provided at the central office similar equipment for each of the other outlying stations. 15 Relays 204 and 205 are associated with the equipment necessary for the central office operator to transmit messages to outlying station B. A key, not shown and corresponding to key 203, is provided to complete a connection from the central office to station B. A broadcast non-locking key 207 is also provided whereby the operator may 20 transmit messages simultaneously to all the outlying stations.

In Fig. 3 four main "receiving only" printers 25 are schematically represented within blocks 301, 302, 303 and 304, and it is understood that the system is not limited to the number of printers shown. Printer 304 is under control of polar relay 305. Relays 306 and 307 serve to make printer 304, when engaged by an outlying station, busy to 30 all subsequent calls from other outlying stations while it remains engaged. Each of the remaining printers 301, 302 and 303 have associated therewith relays corresponding to relays 305, 306 and 35 307. These printers are respectively associated with the contacts on switch bank I. When all the main printers are busy, relay 308 automatically operates to indicate the condition and the operator inserts plug 309 of a cord circuit at the 40 toll switchboard into spring jack 310 which is associated with the lamp 311 corresponding to, say, station A shown in the drawings, whereby the auxiliary printer 312 comprising a sending and receiving unit is connected to the line extending to station A to receive the message. Should the operator desire to originate a call to 45 one or more outlying stations simultaneously, the plug 309 would be inserted in spring jack 313 and the key or keys, corresponding to keys 203 for 50 station A and associated with the desired station or stations, would be operated for connecting the auxiliary printer 312 to the line or lines extending to the desired station or stations. Should it be desired to establish a general broadcast circuit, that is, one including all stations, the printer 312 would be connected by means of plug 309 to 55 spring jack 313 and key 207 would be operated instead of the key corresponding to key 203 and individual to each station of the system.

60 Operation of the system

Having briefly discussed the various circuit elements involved in establishing a connection between a sending and a receiving station, the 65 manner in which the connection is established will now be described in detail. Referring to the drawings, under normal conditions, a deenergized line circuit may be traced from ground 117, 70 break contact and armature of relay 113, through the winding of relay 110, sending contacts 103, break key 106, through the upper winding of relay 112, ring conductor 116, through the lower winding of relay 208, break contact of key 203, outer upper armature and break contact of relay 75

209, upper break contact of relay 210, make-before-break contact of relay 211, to ground 212.

For the purpose of illustration, it is assumed that the subscriber at station A desires to establish a connection to the first idle main printer at the central office. Call key 107 is operated whereby ground 117 is connected to the tip conductor 115, through the upper winding of relay 208, outer lower armature and break contact of relay 222, upper make-before-break contact of relay 211 to grounded positive battery 213. Relay 208 operates and connects ground to the circuit extending through the winding of relay 214 to grounded battery. Relay 214, which is of the slow-release type, operates and applies ground at its inner armature and contact to a circuit extending over the contact and lower outer armature of relay 210, armature and contact of stepping magnet 215 to grounded positive battery 216. A relay 217 is normally held operated by the circuit extending from grounded battery 216, through the right-hand winding of the relay to ground. The application of ground at the inner right-hand armature of relay 214 short-circuits the normally closed circuit extending through the right-hand winding of relay 217, and causes it to release. The release of relay 217 will cause the stepping magnet 215 to operate and thereby move the wipers on banks I, II and III on the stepper switch S one step to their respective second contacts. The energization of the stepping magnet opens the contact at its armature, to remove the short circuit from the right-hand winding of relay 217 causing relay 217 to reoperate. The stepping magnet, therefore, is deenergized again closing the contact at its armature. The closing of the contact of the armature of the stepping magnet again short-circuits the right-hand winding of relay 217 which releases. The release of relay 217 causes the stepping magnet to reoperate thereby causing the wipers of banks I, II and III to move to their respective third contacts. The wipers will continue to step around their respective banks until the wiper of bank II arrives on the contact to which grounded battery is found on the break contact of a relay corresponding to relay 307. Assuming that receiving printers 301, 302 and 303 are busy, relays 314, 315 and 316 will be operated and grounded battery will be found on the fifth contact of bank II because receiving printer 304 is the first idle printer and relay 307 is de-energized. Under this condition a circuit may be traced from grounded positive battery at the make-before-break contact of relay 307, conductor 317, fifth contact of bank II, and its associated wiper, through the upper winding of relay 211, through the left-hand winding of relay 217, to ground at the outer armature of relay 214. This circuit will operate relay 217 and hold it operated preventing any further stepping of the stepper switch wipers. The circuit just traced will operate relay 211, thereby removing ground at the lower make-before-break contact of relay 211 and applying grounded positive battery through the ring conductor 116 in a circuit traceable from battery 318, left-hand armature and contact of relay 308, conductor 319, lower inner armature and contact of relay 211, make-before-break contact of relay 210, outer upper armature and break contact of relay 209, normally closed contact of key 203, through the lower winding of relay 208, conductor 116, through the upper winding of relay 112, closed contact of key 106, transmitting contacts 103, through 75

winding of relay 110, armature and break contact of relay 113, to ground 117. Relays 110 and 112 of station A operate. Relay 110 in operating, closes a circuit extending from one side of the 5 alternating current power supply 108, through the winding of relay 111, armature and contact of relay 110, back to the opposite side of the power supply. Relay 111 operates and at its left-hand contact and armature closes a locking circuit for itself and an operating circuit for the 10 motor 104. Relay 111 closes at its right-hand armature and contact a circuit for energizing the rectifier 109, the rectified current serving to operate relay 113, energizes the lower winding of 15 relay 112, and operates the printer magnet 102 when the armature of relay 112 is in engagement with its associated make contact. The current flowing through the lower winding of relay 112 is considerably less and opposite than that flowing through the upper winding and therefore when the line circuit is open and no current is flowing through the upper winding, the current in the lower winding will hold the armature of relay 112 in the position shown. If the call key 20 107 has not already been released, the starting of motor 104 at station A will be a signal to the subscriber to release key 107. When key 107 is released and relay 113 is operated the loop circuit will be closed from grounded positive battery 318, left-hand armature and contact of relay 308, conductor 319, lower inner armature and contact of relay 211, make-before-break contact of relay 210, upper outer armature and break contact of relay 209, normally closed contact of 25 key 203, through the lower winding of relay 208, ring conductor 116, through the upper winding of relay 112, closed contact of key 106, transmitting contacts 103, through the winding of relay 110, armature and make contact of relay 40 113, normally closed contacts of key 107, tip conductor 115, through the upper winding of relay 208, lower outer armature and break contact of relay 222, make contact and upper armature of relay 211, wiper of bank I on its fifth contact, conductor 218, through the left-hand winding of relay 305, to grounded positive battery. Grounded positive batteries are now connected to opposite ends of the loop circuit which extends through both windings of relay 208. Relay 50 50 208 releases causing the release of relay 214. The release of relay 208 applies ground to a circuit extending over conductor 219, through the winding of relay 210, make contact and lower outer armature of relay 211 to grounded battery. The release of relay 214 tends to release relays 211 and 211, but both relays are held operated. Relay 211 is held operated in a circuit extending from grounded battery, through its lower winding, wiper of bank III on its fifth contact, conductor 60 65 220, motor control contact 329 to ground. The motor control contacts on printer 304 are closed at this time as will hereinafter be described. Relay 217 is held operated in a circuit extending through its right-hand winding because the short circuit around this winding has been removed by the release of relay 214.

The motor control contacts of the printer 304 were closed when the circuit was closed through the wiper of bank I arriving on its fifth contact 70 at the time relay 211 operated. At that time a circuit was closed extending from grounded positive battery, through the left-hand winding of polar relay 305, conductor 218, fifth contact and wiper of bank I, upper armature and make contact of relay 211, break contact and lower

outer armature of relay 222, through the upper winding of relay 208, tip conductor 115, operated contact of key 107 to ground 117. Polar relay 305 is electrically biased to spacing and when no line current is connected to it, its armature lies in the position shown. When the line current flows through the left-hand winding of relay 305, it is considerably greater than the biasing current flowing through the right-hand winding and, therefore, causes the relay armature to engage its contact to close a circuit extending from ground at the relay armature over two parallel paths, one extending through the winding of the printer magnet 321 to grounded battery and the other through the right-hand winding of relay 306 to grounded negative battery. Magnet 321 and relay 306 operate. Relay 306 in operating closes at its right-hand armature an operating circuit for the motor control relay 322 which operates to start the motor of printer 304. The starting of the printer motor closes the motor control contacts 320. The closing of the motor control contacts closes two obvious circuits, one for locking relay 306 and the other for operating relay 307. The operation of relay 307 makes printer 304 busy to subsequent calls. As hereinbefore stated, the closing of the motor control contacts holds relay 211 operated over the fifth contacts of switch bank II.

Relay 210 operates in the circuit hereinbefore described and closes at its lower inner armature and contacts an operating circuit for busy lamp 311 indicating that the printer 304 is engaged. At the upper armature and make contact of relay 210 grounded negative battery 221 is connected to the ring conductor 116 of the line circuit in place of the grounded positive battery 318, puts the line circuit in its position for operation. When grounded negative battery 221 is connected to the line circuit by the operation of relay 210, relay 208 again operates thereby opening the operating circuit for relay 210. Relay 210, however, is maintained in an operated position by a locking circuit which may be traced from grounded battery, lower outer armature and contact of relay 211, through the winding of relay 210, conductor 219, break contact and upper armature of relay 222, conductor 225, contacts and lower inner armature of relay 210 to ground.

Relays 110 and 112 are responsive to message signal impulses transmitted over the line circuit. Relay 110 has no effect on the power supply to printer motor 104 because relay 111 is locked up over its left-hand armature. Relay 112, however, is effective to operate printer magnet 102 so that a home record may be had of the transmitted message.

The contacts of switch bank II to which no printers are connected, are connected to ground and thus made busy, so that the wiper cannot stop on a blank contact.

Disconnection by the subscriber

When the subscriber at station A has completed the transmission of a message, he transmits the double shift signal, or upper case H, which shuts down the motor of printer 104 and opens the motor control contact 320 at printer 304. This operation is well known in the art. The operation of the motor control contact 320 causes relay 211 to release, which in turn releases relay 210. Relay 210 is slightly slow-to-release to permit relay 211 to establish a ground connection at its lower make-before-break contact before relay 210 releases. Relay 210 in re-

leasing, restores the ground at relay 211 to the ring conductor 116 and the line circuit is again normal although the stepper switch S may remain in the position which it is in at the time.

5 *Manual overflow*

In order to provide for overflow in case all the "receiving only" printers are busy, each stepper switch, there being one for each subscriber's line, is arranged to have its first blank contact, that is, the first contact to which no printer is connected, on bank I connected to a jack, such as spring jack 310. Also a busy lamp, such as lamp 311 associated with the line circuit to station A, is connected to a contact of a busy relay, such as relay 210, one being provided for each line circuit or stepper switch. The first blank contact on bank II to which no printer is connected, normally has ground connected to it at the right-hand break contact of relay 308 to prevent the bank wipers from stopping on their respective first blank contacts. As each "receiving only" printer becomes busy, each will cause its relay of the relays 314, 315, 316 and 307 to operate and when all the printers are busy a circuit will close extending from ground, over the left-hand armatures and contacts of the relays 314, 315, 316 and 307, in series, conductor 323, through the winding of relay 308 to grounded battery. Relay 308 operates and disconnects at its left armature the grounded battery 319 from the ring conductor 116 of the subscriber's loop so that the subscriber's printer motor will not operate until the calling line is answered by the operator. A relay, such as relay 308, is provided for each subscriber's line circuit and all operate when all the "receiving only" printers are busy.

When the wiper of bank II engages the first contact to which no printer is connected, a circuit is closed extending from ground at the outer armature and contact of relay 214, through the left-hand winding of relay 217, to the upper winding of relay 211, wiper and sixth contact of bank II, conductor 223, make contact and right-hand armature of relay 308 to grounded battery.

Relays 217 and 211 operate. The operation of relay 217 prevents further stepping of switch S and relay 211 closes a circuit extending from ground 117, operated contacts of call key 107, tip conductor 115, through the upper winding of relay 208, lower outer armature and break contact of relay 222, make contact and upper armature of relay 211, wiper in engagement with the sixth contact of bank I, conductor 224, normal contacts of spring jack 310, through the left-hand winding of relay 324 to grounded battery. Relay 324 operates and closes a locking circuit for itself from grounded battery, break contact and left-hand armature of relay 325, through the right-hand winding of relay 324, over the armature and contact of relay 324, through the lamp 326, through the winding of relay 327 to ground. Lamp 326 lights and relay 327 operates; the operation of the relay causes an alarm 328 to operate. The lamp 326 and the alarm 328 furnish signals to the operator that a particular line is calling for a connection to an idle printer and that all the "receiving only" printers are busy. The operator inserts plug 309 into jack 310 which is associated with the calling line, assumed to be that of station A, whereby the auxiliary printer 312 is connected to the printer 101 at station A. The in-

sertion of plug 309 into jack 310 closes a circuit extending from grounded battery, through the winding of relay 325, normally open contacts and sleeve of jack 310, sleeve conductor of cord 309, through the winding of relay 329. Relays 325 and 329 operate. The operation of relay 325 causes the lamp 326 to become extinguished and alarm 328 to become silent. Relay 329 closes at its left-hand armature and contact the operating circuit for motor control relay 330 and 10 relay 330 operates to start the motor of auxiliary printer 312. The starting of the printer motor closes the motor control contact 331 whereby a circuit is closed from ground at the control contacts, ring conductor of cord 309, ring conductor of jack 310, sixth contact and wiper of bank III, through the lower winding of relay 211 to grounded battery. Relay 211 is therefore locked in an operated position as long as the printer motor is operated.

The insertion of plug 309 into jack 310 also disconnects the path through the left-hand winding of relay 324 and substitutes the path extending over the make contact and right-hand armature of relay 329, through the left-hand winding of relay 332, transmitting contact 333 to grounded positive battery. The operation of relay 325 connects at its right-hand armature and contact grounded positive battery 318, conductor 319, lower inner armature and make contact of relay 211, upper make-before-break contact of relay 210, break contact and outer armature of relay 209, normally closed contact of key 203, through the lower winding of relay 208, ring conductor 116, transmitting side of subscriber's loop circuit, tip conductor 115, through the upper winding of relay 208, outer lower armature and break contact of relay 222, make contact and upper armature of relay 211, wiper in engagement with the sixth contact of bank I, conductor 224, tip of jack 310 and plug 309, make contact of relay 329, through the left-hand winding of the electrically biased relay 332, transmitting contacts 333 to grounded positive battery. The loop circuit has grounded positive battery on both ends which causes relay 208 to release, thereby connecting ground at its armature and contacts to the operating circuit of relay 210, as hereinbefore described. Relay 210 operates to disconnect grounded positive battery 318 from the ring and to substitute therefor grounded negative battery 221 thereby putting the loop circuit in condition for operation at which time the motor at the subscriber's station A starts operating and the key 107 is restored to normal. Relay 208 is deenergized momentarily only because of grounded negative battery being connected to the loop circuit by relay 210. Relay 210 is maintained operated in a circuit extending from grounded battery at the outer lower armature and contact of relay 211, through the winding of relay 210, break contact and upper armature of relay 222, conductor 225, to ground at the contact and lower inner armature of relay 210. Relay 210 in operating, also closes at its lower inner armature a circuit for operating the busy lamp 311 at the toll switchboard.

When the message is completed the disconnection takes place in the same manner as when the line is connected to an idle "receiving only" printer.

Broadcasting

When it is desired to broadcast, the auxiliary

printer 312 may be used. The plug 309 of the cord circuit is inserted into broadcast jack 313, common to all the subscribers' lines employed in the system, whereby the auxiliary printer is connected for operation.

Group broadcasting

If it is desired to transmit to a selected group of subscribers' stations, the operator at the toll 10 switchboard will depress a non-locking key corresponding to key 203, for each station to be included in the broadcast. The depressing of, say key 203, assuming that station A is to be included, closes an operating circuit for relay 222, 15 extending through its upper winding to grounded battery. Relay 222 operates and closes a locking circuit for itself, extending through its make contact and lower inner armature, conductor 226, through the winding of relay 210, conductor 219, 20 to ground at the break contact and upper armature of relay 208. Relay 208 is deenergized because grounded positive batteries are connected to both ends of the loop circuit of station A, battery 227 being connected at one end by switch 25 203 and battery 213 being normally connected at the other end. Relay 222, in operating disconnects at its lower outer armature and break contact the circuit normally extending to grounded positive battery 213 and substitutes therefor the 30 grounded positive battery 231 at the armature of polar relay 201. Relay 210 operates and closes at its lower inner armature and contact a circuit having two parallel paths, one extending from ground, conductor 225, upper armature and 35 make contact of relay 222, through broadcast lamp 227 to grounded battery, and the other, through busy lamp 311 through grounded battery. Lamps 227 and 311 light indicating to the operator that the loop circuit extending to station A is busy for broadcast.

If broadcast lamp 227 remains lighted, the broadcast key 203 is released and therefore closes its normally closed contact, whereby grounded negative battery 221 is connected over the upper 40 armature and make contact of relay 210, break contact and upper outer armature of relay 209, normally closed contact of key 203, through the lower winding of relay 208, to the ring conductor 116 of the loop circuit to station A, tip conductor 115, through the upper winding of relay 208, outer lower armature and make contact of relay 222 to grounded positive battery 231 at the armature of relay 201. Relay 208 being of the differential type does not operate and relay 222 remains operated to its locking winding.

The insertion of plug 309 in the broadcast jack 313 closes an operating circuit for relay 228 which is common to the broadcast circuit of all the subscribers' stations, the circuit being traceable 45 from ground, through the winding of relay 329, sleeve of plug 309 and jack 313, conductor 334, through the winding of relay 228, conductor 229, to grounded battery 335. Relay 329 operates as hereinbefore described to start the motor of 50 printer 312. Relay 228 operates and closes a circuit extending from ground at its armature, through the right-hand winding of relays 205, 202, etc. in series, one of which relays is provided for each subscriber's circuit, conductor 230, operated contact 337 to battery 335.

The operation of relay 329 closes the tip or transmitting circuit from grounded battery at transmitting contacts 333, through the left-hand winding of relay 332, right-hand armature and 55 contact of relay 329, tip conductor of plug 309

and jack 313, conductor 336, through the left-hand windings, in series, of relays 202, 205, etc. Relays 202, 205, etc. operate to the positions shown in response to current flowing from the grounded battery at transmitting contacts 333. The currents respectively flowing through the windings of each of relays 202, 205, etc. oppose each other, the current in the left-hand winding predominating. Each of the relays 202, 205, etc. respond to the signal impulses transmitted from 10 printer 312. Relays 201, 204, etc. respond to their respectively associated relays 202, 205, etc. and transmit the signals to their respectively associated loop circuits provided such circuits are selected for the broadcast by operating the respective keys, such as key 203, shown for the loop circuit to station A.

When the broadcast message is completed, a stop signal which may be the upper case H, is transmitted from the printer 312 or a printer of 20 any one of the stations connected in the broadcast circuit whereby the motor control contacts in each printer are open. The opening of the motor control contacts at the receiving station of the broadcast circuit stops their respectively associated motors. In the case of station A, relay 113 releases and ground 117 is thereby connected to the tip side of the station loop so current flows through the lower winding only of relay 208. Relay 208 operates causing the release of relays 30 210 and 222. The release of relay 222 extinguishes the broadcast lamp 227 and the release of relay 210 extinguishes busy lamp 311. The switchboard operator at the central office then removes plug 309 from jack 313. 35

Complete broadcast

A complete broadcast, that is a broadcast wherein all stations are included, may be made in the same manner as described above for the 40 group broadcast except that instead of depressing keys, such as key 203 individual to the subscriber's station, a general broadcast non-locking key 207, common to all the subscribers' stations is operated whereby a series of relays, such as relays 209, 206, etc., which are individual to the subscriber's station, are operated. Each of the relays 209, 206, etc. automatically performs and causes to perform the same function that each of the manually operated keys, such as key 203, 50 performs in completing a group broadcast. The remainder of the operation is the same as described above for the group broadcast.

What is claimed is:

1. In a signal transmission switching system, 55 the combination of a plurality of sending stations, a plurality of receiving stations, and an auxiliary sending and receiving station, rotary devices individual to each of said sending stations for selecting any one of said receiving stations, a normally deenergized circuit extending from each of the sending stations to each of said devices, operating means at each of said sending stations arranged when operated by a single movement, to close one of said circuits and to thereby cause one of said devices to automatically select an idle one of said receiving stations for connection to said one of said circuits, and means connected to each of said rotary devices and adapted when all receiving stations are busy, for connecting said auxiliary station to the sending station connected to the last operated rotary device. 60

2. In a signal transmission switching system, 65 the combination of a plurality of sending sta-

70

75

tions, a plurality of receiving stations, and an auxiliary sending and receiving station, a signal printer at each of said stations, a rotary device individual to each of said sending stations for selecting any one of said printers at the receiving stations, a normally deenergized circuit extending from each of said sending stations to each of said devices, operating means at each of said sending stations arranged when operated by 10 a single movement to close one of said circuits and to thereby cause one of said devices to automatically select an idle printer at one of said receiving stations, and indicating means for informing an operator that a sending station has 15 been connected to an idle printer at one of said receiving stations, other indicating means for informing the operator when all the printers at said receiving stations are busy, and means connected to each of said devices and adapted, when 20 all receiving stations are busy, for connecting said auxiliary station to the sending station connected to the last operated rotary device.

3. In a signal transmission switching system, the combination of a plurality of sending stations 25 and a plurality of receiving stations, a signal recording device at each of said stations, rotatably stepping devices individual to each of said sending stations for selecting any one of said recording devices at the receiving stations, a normally deenergized circuit extending from each of said 30 sending stations to each of said selecting devices, operating means at each of said sending stations arranged when operated by a single movement, to close one of said circuits and to thereby cause 35 the selecting device connected to said closed circuit to automatically select an idle recording device at one of said receiving stations, indicating means for informing an operator that a sending station has been connected to an idle recording device at one of said receiving stations, other 40 indicating means for informing the operator when all the recording devices at said receiving stations are busy, and another signal device arranged to be connected by the operator to said circuit when all the other recording devices are 45 busy, for receiving the signals.

4. A signal transmission system according to claim 3 wherein the signal device connectible to the circuit by the operator is adapted to transmit 50 signals to two or more of said recording devices at said sending stations simultaneously.

5. A signaling switching system comprising a plurality of calling stations, a called station, a signal transmitting and receiving device and driving means therefor at each of said calling stations, a plurality of signal receiving devices and driving means respectively provided therefor at the called station, switch means at each of the calling stations for establishing a connection between its associated signal transmitting and receiving device and the first idle signal receiving device, circuit closing contacts included in said signal receiving device for operating the driving means therefor in response to the establishment 60 of said connection, and other switch means in each of the signal transmitting and receiving devices for sending a special code signal to the operating signal receiving device selected in said connection whereby said circuit closing contacts 65 are opened to stop the operation of the driving means of said operating signal receiving device.

6. In a signal transmission switching system, the combination of a central office, a plurality of remote stations, a signal transmitting and receiving printer and a driving motor therefor at each of said stations, rotary selecting mechanisms at said central office, individual to said stations, normally deenergized circuits interconnecting said stations and said selecting mechanisms, calling means at each of said stations for energizing one of said circuits whereby the operation of one of said selecting mechanisms is started, a plurality of signal receiving printers and motors respectively provided therefor at said central office, a plurality of relays for respectively controlling said printers and motors therefor, said relays being arranged to be automatically connected in successive order to one of said circuits in response to the operation of the selecting mechanism connected thereto, said motors for said receiving and said transmitting and receiving printers arranged to operate, in response to the establishment of a connection between said selecting mechanism and said receiving printer, and normally inert motor control means for said receiving printer arranged to operate when the motor therefor operates, said control means being arranged to restore to normal in response to a special code signal transmitted by the transmitting and receiving printer associated with said one of said selecting mechanisms whereby said selecting mechanism, said receiving printer and said transmitting and receiving printer are rendered available for another call. 10 15 20 25 30 35

7. In a signal transmission system, the combination according to claim 6, wherein is provided at the central office an auxiliary signal sending and receiving printer, and driving means therefor with means adapted when all the signal receiving printers are busy, for connecting said auxiliary printer to the signal transmitting and receiving printer at the calling station, the driving means for said auxiliary printer being arranged to stop in response to a special code signal transmitted by the signal transmitting and receiving printer at said calling station. 40 45 50 55

8. In a signal transmission system, the combination according to claim 6, wherein is provided at the central office indicating means for informing an operator that a signal transmitting and receiving printer at a remote station has been 50 connected to an idle signal receiving printer at the central office, and other indicating means for informing the operator when all the signal receiving printers at the central office are busy.

9. In a signal transmission system, the combination according to claim 6, wherein is provided at the central office an auxiliary signal transmitting and receiving printer and driving means therefor, with means for connecting said auxiliary printer to the transmitting and receiving printer at one or more remote stations simultaneously and for starting the driving motors of the transmitting and receiving printers at said remote stations, and means included in each of the transmitting and receiving printers at the remote station responsive to a special code signal transmitted from said auxiliary printer for stopping the driving motors of the transmitting and receiving printers at the remote stations simultaneously. 60 65 70 75
